UNITED STATES PATENT OFFICE

ARTHUR M. TROGNER, OF EAST ORANGE, NEW JERSEY, ASSIGNOR, BY MESNE ASSIGNMENTS, TO FEDERAL TELEGRAPH COMPANY, A CORPORATION OF CALIFORNIA

WAVE-CHANGER SYSTEM

Application filed February 11, 1929. Serial No. 339,154.

This invention relates to signaling systems in general. More specifically this invention relates to inductance arrangements employed in signaling systems.

An object of this invention is to provide an inductance arrangement for signaling systems whereby the operating frequency of the signaling system may be readily changed.

Another object of this invention is to provide an inductive coupling arrangement for signaling systems whereby the inductance of the entire inductive coupling arrangement may be varied simultaneously.

Still another object of this invention is to provide means associated with the inductances of the tuned circuits of signaling systems whereby the operating frequency of the signaling system may be readily varied from one predetermined value to another.

Other objects and features of this invention will be apparent to those skilled in the art to which this invention pertains from the following specification and the annexed claims.

In signal transmitting systems it is often desirable to change the operating frequency of the apparatus rapidly. Usually this is accomplished by changing the number of turns of inductance in the resonant circuits of the transmitting system. In this invention, I provide means whereby both the inductance included in the resonant circuit and the coupling inductance are varied simultaneously. This is highly desirable especially in transmitting systems adapted for operation on widely separated frequencies as is now commonly done in high frequency signaling systems.

According to this invention an inductance system comprising a plurality of concentrically mounted inductance coils is rotatably mounted with respect to a contacting arrangement. Arc shaped members are disposed upon portions of the outermost inductance. Connections are provided between the arc shaped members and interiorly disposed inductance units. The stationary contacting arrangement is provided with members for connecting selected ones of the arc shaped members into circuit as the inductance system is rotated and as connections to dif-

ferent portions of the outermost inductance are changed.

In the drawings Figure 1 shows a perspective view of an inductance system embodying this invention; Fig. 2 is across-sectional view along the line 2—2 of Fig. 3 of a modification of this invention and Fig. 3 is a sectional view along the line 3—3 of Fig. 2 of the inductance system in front elevation.

Referring to Fig. 1 of the drawing in detail, reference numeral 1 designates an inductance supporting frame having end pieces 2 and 3 and longitudinally disposed across pieces 4, 5 and 6. Rotatable member 7 is supported by the end pieces 2 and 3. Inductance frames 8 and 9 are supported upon the rotatable member 7. Contacting members 10, 11 and 12 are positioned upon the cross piece 4 which is of conducting material, such as brass, bronze or copper, for engagement with the inductance turn engaging members 10' and 11'. Contacting members 13, 14, and 15 are positioned upon the cross piece 5, which is also of conducting material, for engagement with members similar to 13' and 14' which are positioned upon the turns of the inductance winding supported by the frame 8. A bar member 16 is attached to the end piece 2. Contacting members 17, 18 and 19, are positioned upon the bar member 16 which is of conducting material. Metallic straps 17', 18' and 19' are mounted upon the inductance frame 8. Lug members 17'', 18'' and 19'' are positioned upon the metallic straps 17', 18' and 19' for engagement with the contacting members 17, 18 and 19. Connections 20, 21 and 22 are provided between the strap members 17', 18' and 19' and certain turns of the inductance mounted upon the frame 9. Metallic strap 23 is mounted upon the frame 8. A connection between the metallic strap 23 and the inductance mounted upon the frame 9 is provided. Members 24, 25 and 26 are positioned upon the strap 23 at positions such that the contacting member 28 which is mounted upon the metallic bar member 27 will engage member 24 when contacting member 18 engages member 18'', contacting member 28 will engage member 25 when 17 engages 17'' and member 26 when

19 engages 19''. Members similar to 29 are provided at the end of the inductance mounted on frame 8 for engagement with the contacting member 31 which is mounted upon the conducting bar 30. Lever 32, which may be replaced by any belt and pulley, gear or chain mechanism, is employed for turning the inductance frames 8 and 9 with respect to the frame 1. A scale having graduations A, B, C which designate the wave length or frequency of operation for particular settings of the inductances may also be provided.

In Fig. 2 a modification of this invention adapted for use in a symmetrical electron discharge device circuit arrangement, such for example as a push-pull amplifier circuit, is illustrated. In this modification conducting bar members 51 and 52 corresponding to member 16 of Fig. 1 are attached to the end pieces 53 and 54 of the inductance system mounting frame. Strap members 55, 56, 57 and 58, 59, 60 corresponding to strap members 17', 18' and 19' of Fig. 1 are provided at each end of the inductance frame 61. Connections 63, 64, 65 and 66, 67, 68 are provided between the members 55, 56, 57 and 58, 59, 60 and selected points on inductance 73 respectively. Bar members 51 and 52 are provided with contacting members 55', 56', 57' and 58', 59', 60', respectively for engaging projecting members attached to strap members 55, 56, 57 and 58, 59, 60, respectively. Bar member 69 is attached to the end piece 53. Contacting member 70 is positioned upon the bar 69 for engaging projecting members positioned upon the conducting strap 71. A connection 72 is provided between the strap 71 and the mid turn of the inductance 73.

In Fig. 3 a cross-sectional view in front elevation of the modification illustrated in Fig. 2, is shown. In operation the bar members 74, 75 and 76 correspond to members 4, 5 and 6 of Fig. 1. Contacting members 74', 75' and 76' for engaging inductance turn engaging members 74'', 75'' and 76'' respectively are positioned upon the bar members. Conducting bar member 52 is attached to the end piece 54 for supporting contacting members similar to 60' for successively engaging the projecting members 58', 59' and 60' which are positioned upon the strap members 58, 59 and 60. Conducting bar member 77 is also supported by the end piece 54 of the inductance frame. Contacting member 78 is positioned upon the bar 77 for successively engaging turn engaging members on the inductance mounted on frame 61.

The operation of the inductance arrangement comprising this invention is best understood by a reference to Fig. 1 of the drawing. By way of illustration an inductance system having only three settings A, B and C is shown. More settings may be employed if desired and if a greater number of operating

frequencies are desirable. When the indicator 32', which may be a pointer as shown or a frequency calibrated dial, is set upon a certain setting, as A for example, certain ones of the contacting members as 10, 13, 19, 28 and 31 are in engagement with turn selecting members 10', 13', 19'', 26 and 29 respectively. When the indicator is turned to position B different portions of the inductances mounted on frames 8 and 9 will be included in circuit since the same or different contacting members are in engagement with different turn selecting members.

Connections between the signal transmitting system and the inductances are established through conductors D, E, F, G, H and I attached to bar members 4, 5, 6, 16, 27 and 30, respectively.

While I have described my invention in some of its preferred embodiments I realize that modifications thereof may be made, it is therefore understood that the embodiments of my invention are not to be limited in scope to the foregoing specification and drawing but only as defined by the annexed claims.

What I claim as new and desire to secure by Letters Patent of the United States is as follows:

1. In a wave changing system for high frequency signaling system the combination of a plurality of inductance units, one of which surrounds another thereof, contacting members positioned with respect to said inductance units and means connected to the turns of said inductance units for engaging said contacting members, said inductances being coaxially disposed with respect to each other.

2. In a wave changing system for high frequency signaling systems the combination of a plurality of inductance units, one of which surrounds another thereof, contacting members positioned with respect to said inductance units, means connected to certain turns of the inductance units for engaging said contacting members, and means for rotating said inductance units, said inductance units being coaxially disposed.

3. In an inductance system of the class described, the combination of a plurality of concentrically disposed inductance units, one of which surrounds another thereof, mounted upon a rotatable member, contacting members mounted upon members stationary with respect to said inductance units, and means connected to certain turns of said inductance units for engaging said contacting members.

4. In an inductance system of the class described, the combination of a plurality of concentrically disposed inductance units, one of which surrounds another thereof, mounted upon a rotatable member, contacts connected to selected turns of said inductance units, contacting members for engaging said contacts, said contacting members being positioned upon a plurality of members longitudi-

nally disposed of said outermost inductance unit.

5. In an inductance system of the class described the combination of a plurality of concentrically disposed inductance units, one of which surrounds another thereof, mounted upon a rotatable member, contacts connected to selected turns of said outer inductance unit, contacting means for engaging said first mentioned contacts, means for connecting said inner inductance into circuit, connections between selected turns of said inner inductance and said last mentioned means, and additional contacting members 10 for engaging said last mentioned means.
